INDICATOR DEVICE FOR VISIBLE PUMPS

Leo E. Rush, La Fayette, Ind., assignor to M. L. Joyce, La Fayette, Ind.

Application August 11, 1933, Serial No. 684,639

11 Claims. (Cl. 116—118)

This invention relates to an indicator device for visible dispensing pumps.

The chief object of this invention is to provide an indicator device which is of unitary character and which is adapted for mounting upon the overflow tube or standpipe that is usually centrally positioned within the glass cylinder of a visible dispensing pump suitable for the dispensing or sale of gasoline or the like.

10. One object of the invention is to provide a device which is rotatable, when desired, within said glass cylinder, so that the entire interior surface of the glass cylinder may be cleaned without removing the indicator device from the cylinder and thereby eliminate the possibility of subsequent erroneous measurement due to poor visibility of the target or indicator. Heretofore indicating devices usually have been rigidly associated with visible pumps of this character. The interior of the cylinder usually was not cleaned by the attendant in the vicinity of the indicators, because the indicators were not removed, or if removed, there was always present the danger of the indicating device, or indicators, being repositioned in erroneous position or if the interior surface of the cylinder were cleaned in the vicinity of the indicators, such cleaning frequently subjected the indicators to movement with respect to the support so that a true indication was not obtainable thereafter, or if cleaning in the vicinity of the indicators were too laborious, the interior of the bowl immediately in front of the indicators did not receive the cleaning which it should have received and thereby the visibility of the indicators was progressively diminished although full visibility of the indicators was one of the primary purposes for the cleaning of the bowl.

40. The second object of the invention is to provide a permanent installation which, when once positioned in the cylinder, or bowl, as it is commonly called, may remain there indefinitely and yet permit cleaning of the bowl throughout the entire interior surface without the necessity of removing the indicating device unit or subjecting the same to the possibility of distortion in the cleaning operation.

The chief feature of the invention consists in the accomplishment of the aforesaid objects.

50. Another feature of the invention consists in, when desired, the provision of means for normally retaining the indicating device unit in a predetermined selected position, which position may be readily changed and the device retained in the changed position.

55. The full nature of the invention will be under-

stood from the accompanying drawing and the following specification and claims:—

In the drawing, Fig. 1 is a central sectional view through the visible bowl portion of a conventional representation of a glass bowl, or cylinder of a dispensing pump with the indicator device unit shown in elevation.

Fig. 2 is an enlarged bottom plan view of the lower spider of the unit.

Fig. 3 is an enlarged transverse sectional view of a portion of the upper spider and its association with the overflow tube of the dispensing pump, and illustrates in detail one form of adjustable support for the unit and one form of selective locking device.

10. In the drawing 10 indicates the conventional bowl base of a liquid dispensing pump which is of the visible type and the chamber 11 thereof is formed by a glass cylinder 12, commonly called the bowl. The top of the cylinder is closed by 20 the ring 13 which supports a cover 14. It is herein shown of detachable type but may be of the hinged type so that access may be readily had to the interior of the bowl. The base 10 also supports the centrally positioned overflow tube 25 15 which includes a cap 16 and therebeneath a mouth 17 having the lower most draining level 18.

15. All of the aforesaid is a conventional illustration and description of the upper and visible portion of a so-called visible dispensing pump.

20. The invention consists in providing an indicator device that is of unitary character and may be readily associated with the aforesaid standpipe or overflow. The operation of the visible pump is well known but may be briefly stated as follows:—

25. The dispensing attendant may either manually or through power means fill the bowl until the liquid therein overflows through the mouth 17 and then the supply is discontinued. The liquid will drain out of the bowl until the top level 40 thereof coincides with the lower edge 18 of the mouth 17. Then the attendant opens the valve on the hose, not shown, and supplied from discharge 19 and holds said valve controlling the discharge open until the liquid level falls to the desired elevation, coinciding with the amount purchased, as represented by the different levels indicated by the respective indicators. The use of indicators for indicating the respective levels and the permanent supporting of the indicators upon a single support and within the container is specifically disclaimed.

30. As set forth herein before, with respect to the objects of this invention upon the interior of the visible bowl, usually a glass cylinder, there

5 accumulates a scum, or the like, which interferes with the visibility and also is liable to convey to the purchaser the idea that the gasoline has a color which it does not actually have. Therefore, the cleaning of the interior of such a bowl is highly desirable. Heretofore, with the rigid support and permanently attached indicator devices, there was introduced the possibility of deformation of the respective indicators, or the erroneous 10 repositioning of the same, if the entire indicator device were removed and replaced after bowl cleaning.

15 The present invention contemplates the construction of an indicator device as a unitary arrangement, and which is mounted to swivel on the overflow pipe.

20 In the drawing 20 indicates a collar from which is divergently directed a plurality of arms 21 each terminating in a socket or opening 22. The aforesaid 25 may be made as a casting or as a stamping. As shown in Fig. 1, the arms lie in substantially the same plane as the collar portion 20. The upper member is similar thereto, except that rising from the collar 23 are the outwardly and 25 upwardly directed arms 24, each terminating in an opening 25. The openings in the two spiders are arranged to register and suitably connecting the spiders by operative connections at said openings are the indicator sustaining rods 26.

30 These indicator devices are shown in front elevation and also in partial end elevation. They are rigidly and relatively permanently secured to the rods. The whole structure, therefore, consists of a cage comprising an upper and lower 35 spider and a plurality of connecting indicator supporting rods, preferably three or four in number. Herein but three are illustrated.

40 The collar portions 20 and 23 are telescopically mounted upon the overflow tube 15 and as a result thereof, normally would have free swiveling action about the axis of the overflow tube so that the indicator device as a unit may be shifted angularly on said tube to permit full cleaning of 45 the interior surface of the bowl without the attendant and/or the cleaning implement, usually a rag or the like, engaging any one of the indicators.

50 The aforesaid constitutes the simplest form of the invention. If desired, an additional means may be provided for accurately positioning the indicator unit so that the uppermost indicators will all have their specific level indicating portions coinciding with the level 18 of the mouth of the overflow pipe. Herein the uppermost indicator indicates said level.

55 Herein a conventional form of support is shown in Fig. 3 and the same includes a flange plate structure having the flange portion 27 and the collar portion 28, said structure being split as at 60 29 and being provided adjacent the split and at the collar portion 28 with a pair of ears 30 and 31, the former being threaded as at 32 and the latter being apertured as at 33. A clamping bolt 34 has a portion of the body of the bolt extending 65 through the aperture 33 and the end has threaded engagement with the threaded opening 32. With this type of construction, therefore, it is possible to clampingly mount the flange collar 27-28 on the overflow standpipe some distance 70 below the mouth 17 and this collar will be clamped in such position on the pipe so that the level indicating portion of the uppermost indicators will indicate exactly the level 18 of the overflow pipe mouth.

75 If and when desired, additional means may be

provided which is adapted to readily retain the indicator cage in the angular adjusted position so that maximum visibility to the purchaser is assured. Herein a conventional form of locking device is illustrated and may be briefly described as follows:—

80 The flange 27 is provided with a plurality of apertures or recesses. Herein apertures are illustrated. They are indicated by the numeral 35. One arm 24 of the upper spider construction 10 mounts a pivot pin 36, the opposite projecting ends of which are associated with the bifurcations 37 of a locking mechanism having a depending or locking bolt portion 38 and an upstanding finger engageable portion 39. The collar portion 15 23 is apertured as at 40 and the portion 38 is adapted for reciprocation in said aperture 40 so that the end of the locking bolt portion 38 may seat in one of the recesses 35 selected. A spring 15 for retaining the locking mechanism in locking 20 position may be provided. However, as herein illustrated, the weight of the same is such that it will normally tend to retain the locking bolt portion 38 in the locking position.

25 When it is desired to free the cage for swiveling or positioning in another position for cleaning the interior of the bowl or otherwise, the finger portion 39 is engaged and the bolt portion 38 is retracted from the recess 35 and the cage is then free to swivel. This lever mechanism associated with the lock bolt may be so arranged that when the locking lever has been manually tilted into the unlocked position, it will normally be retained therein by gravity in 30 said position. In other words, this mechanism may be so constructed that no springs are necessary and that the bolt will be self maintained by reason of gravity in either its locking or unlocked position. The locking mechanism may be applied to the lower spider but preferably it is 35 associated with the upper spider, since it is more accessible in that position. It is, of course, understood that the cover 14 is either detachably or hingedly associated with the ring 13 in any conventional manner, such as is commonly found in visible dispensing pumps of this character 40 now available.

45 No claim is made for the specific form of indicator nor as before mentioned, the positioning of a series of indicators upon a common support 50 mounted within the bowl of a visible pump nor a composite indicator device that is detachable and removable from and/or rotatable within the visible bowl.

55 The invention claimed is:—

60 1. In a visible pump having an upstanding member within the visible bowl thereof, an indicator device unit including a top structure, a bottom structure, elongated elements connected at opposite ends to both structures, and indicators rigidly secured in spaced relation to certain of said elements, said unit having pivotal movement upon the upstanding member and supported thereby.

65 2. In a visible pump having an upstanding overflow pipe within the visible bowl thereof, an indicator device of cage formation pivotally mounted upon the pipe for arcuate movement and including a set of indicators in spaced relation.

70 3. In a visible pump having an upstanding overflow pipe within the visible bowl thereof, the combination of an indicator device of cage formation, means pivotally mounting said device upon the pipe for arcuate movement, said 75

- device including a set of indicators in spaced relation, and means for securing said cage in predetermined position upon said pipe.
4. In a visible pump having an upstanding overflow pipe within the visible bowl thereof, the combination of an indicator device of cage formation, means pivotally mounting said device upon the pipe for arcuate movement, said device including a set of indicators in spaced relation, and means for securing said cage in predetermined rotative position upon said pipe, said first mentioned means including an axially adjustable member mounted upon said pipe.
5. In a visible pump having an upstanding overflow pipe within the visible bowl thereof, the combination of an indicator device of cage formation, means pivotally mounting said device upon the pipe for arcuate movement, said device including a set of indicators in spaced relation, and means for securing said cage in predetermined elevated position upon said pipe, said first mentioned means including a locking device for securing the cage upon the pipe in angularly adjusted position.
6. In a visible pump having an upstanding overflow pipe within the visible bowl thereof, the combination of an indicator device of cage formation, means pivotally mounting said device upon the pipe for arcuate movement, said device including a set of indicators in spaced relation, and means for securing said cage in predetermined position upon said pipe, said means including an axially adjustable member mounted upon said pipe for cage elevation positioning and a locking device for securing the cage upon the pipe in rotative adjusted position.
7. In a visible pump having an upstanding overflow pipe within the visible bowl thereof, the combination of an indicator device of cage formation, means pivotally mounting said device upon the pipe for arcuate movement, said device including a set of indicators in spaced relation, and means for securing said cage in pre-

determined elevated position upon said pipe, said second mentioned means including an axially adjustable member mounted upon said pipe, said first mentioned means including a locking device for securing the cage in angularly adjusted position, said locking device and said axially adjustable member having a cooperative relation therebetween.

8. In a visible pump having a visible bowl, an upstanding member therein and a cover for the bowl movable into non-covering position to expose the bowl interior, the combination of a plurality of indicators, and means supporting said indicators in spaced relation and pivotally mounted upon said upstanding member for the purpose set forth.

9. In a visible pump having a visible bowl, an upstanding member therein and a cover for the bowl movable into non-covering position to expose the bowl interior, the combination of a plurality of indicators, means supporting said indicators in spaced relation and pivotally associated with said upstanding member for the purpose set forth, and other means associated with the last mentioned means for securing said first mentioned means in predetermined angularly adjusted position.

10. An indicator cage construction comprising a bottom spider, a top spider the arms of which are directed upwardly and outwardly, the arms of both spiders being in radial registration, elongated members connecting the ends of the registering arms, and indicators secured in spaced relation to a plurality of said members.

11. An indicator cage construction comprising a bottom spider, a top spider the arms of which are directed upwardly and outwardly, the arms of both spiders being in radial registration, elongated members connecting the ends of the registering arms, indicators secured in spaced relation to one of said members, and a locking member carried by the upper spider.
